HAIR EXTRACTOR MECHANISM

Julius Fichter, South Euclid, Ohio, assignor to
Maurice M. Cohen, Cleveland, Ohio

Application April 22, 1947, Serial No. 743,156

6 Claims. (Cl. 128—355)

1

The present invention relates to a power driven hair extractor and it is an improvement on the hair extractor disclosed in U.S. Patent No. 2,413,576.

An object of the invention is to provide a hair extractor of the type disclosed in the above mentioned patent in which the hair gripping members, which rotate about a common axis and move toward and away from one another for gripping and displacing hair entering between the members, can be separated substantially further apart than when operating to extract hair and maintained separated by a manually operated member to permit dirt and foreign matter to be removed from between the hair gripping surfaces of the gripping members.

Another object of the invention is to provide a dirt retaining groove in one of the hair gripping members for preventing dirt from working out of the mechanism and between the hair gripping surfaces.

Other objects and advantages of the invention will be apparent from the following description of a preferred form of the invention, reference being made to the accompanying drawings in which:

Fig. 1 is a longitudinal view in section of a hair extractor;

Fig. 2 is a fragmentary view similar to that of Fig. 1, but showing certain parts of the hair extractor in different positions; and

Fig. 3 is a fragmentary top view of the extractor.

The hair extractor shown in the drawings consists of a tubular handle member 5 which may be of any suitable material and formed of such size and shape that it can be easily held and manipulated by the hand. A rod 6 having a sleeve 7 is journaled in the handle by suitable pin bearings 8, and one end of the rod projects from one end of the handle. The projecting end of the rod has a head 9 formed thereon, which head provides a laterally projecting annular face 10. Also, a peripheral groove 12 is formed about the rod 6 adjacent to the face 10, but spaced slightly therefrom. The purpose of the groove will be brought out hereinafter.

The sleeve 7 is rotatively coupled with the rod 6 by pins 14 and 15 which extend through the rod, and the end portions of which project through longitudinally extending slots 16 and 17, respectively, in the sleeve. Thus, the sleeve 7 will rotate with the rod 6 and at the same time it may reciprocate longitudinally on the rod by means of the slots 16 and 17.

2

Longitudinal movement of rod 6 to the left is prohibited by the thrust bearing 22, one race 23 of which is connected with pin 45. Movement of the rod 6 in the opposite direction is restrained by a compression spring 26 interposed between a ring 25 connected to rod 14 and a thrust bearing 27. The rod 6 is adapted to be driven by a coupling member 30 that may be connected at 31 with a flexible drive shaft, not shown.

The sleeve 7 is adapted to be reciprocated on the rod 6 as the rod and sleeve rotate, and the outer end of the sleeve will be moved by a resilient force against the face 10 to grip hair between its end edge 32 and the face 10. The sleeve will subsequently be withdrawn after it has rotated through approximately 120° to release the hair. This reciprocation of the sleeve 7 is effected by a drum-shaped cam member 34 mounted on the sleeve. The cam member has a keyway 35, into which a lug 36 on the sleeve projects so that the cam will be driven by the sleeve and at the same time there may be relative longitudinal movement between the cam and sleeve. The cam member 34 has a cam groove 37 therein and a cam follower 38 projects into the groove. The cam follower 38 comprises a roller journaled on a plug 39 threaded into an opening in the handle 5 so that the follower will project into the cam groove. The cam groove has one portion offset so that as the cam 34 rotates, the fixed follower 38 will cooperate with the edges of the cam groove to cause the cam member to reciprocate longitudinally of the sleeve 7. The upper end of the plug 39 is covered by a cap 39' which conceals the plug for preventing tampering therewith.

A compression spring 40 is interposed between the cam member 34 and a collar 41 fixed to the sleeve by a set screw 42. The spring 40 continually urges the sleeve to the right, as viewed in the drawings, so that the end of the sleeve will abut the hair gripping face 10 with a yielding force to grip hair with sufficient firmness to extract the hair by the rotary motion of the rod and sleeve. The sleeve is moved in the opposite direction by the cam member 34 engaging a stop member 44, which is attached to the sleeve 7 by a set screw 45. The sleeve 7 will be moved from the face 10 a distance to release hair gripped between the sleeve and face and to receive unpulled hairs, but not such distance as to uncover the groove 12. For example, this movement is approximately 0.018 inch. Thus, the sleeve will be urged into the hair gripping position by a resilient action but will be moved to the hair releasing position by a positive action. It will be

understood that the sleeve will be moved in opposite directions once during each revolution thereof.

As the extractor is operated, there will be a tendency for dirt and the like to work outwardly along the rod 6 and appear between the end of the sleeve 7 and face 10 where it would be transferred to the skin by the user, which is of course undesirable. The groove 12 catches and retains this dirt and other material before it enters the space between the sleeve end and face 10. Thus, this dirt, which may be of a greasy consistency, will be arrested before it is smeared or deposited on the skin of the user.

Also, bits of hair, dry skin and the like are apt to collect between the face 10 and the end edge 32 of the sleeve 7 and interfere with efficient operation of the extractor. In order to permit easy removal of the material collected between the hair gripping surfaces 10 and 32 and to clean out the groove periodically, I have provided manually operable means for retracting the sleeve beyond the groove so that a cloth or cleaning tissue may be inserted between these surfaces and into the groove as the sleeve and rod rotate. This means comprises a flange 41 formed on the stop member 44 and an eccentric actuator for engaging the flange and moving the member 44, together with the sleeve 7, to the left. The eccentric actuator consists of a cylindrical plug 49 rotatably mounted in an opening in the handle 5. The inner face of the plug 49 has a roller 50 mounted thereon eccentric to the axis of rotation of the plug so that when the plug is in the position shown in Fig. 1, the roller is out of contact with the flange 41, but when the plug 49 is rotated through 180°, as shown in Fig. 2, the roller 50 will engage the flange and move the member 44 out of contact with cam 34 and cause the outer end of the sleeve 7 to move to a position in which the groove 12 is uncovered. For example, the edge 32 may be separated $\frac{1}{8}$ " from face 10. This retraction of the sleeve may be effected while the rod and sleeve are rotated and by merely inserting a cloth or tissue between the surfaces 10 and 32 and into the groove, the dirt will be removed, assisted by rotation of the rod and sleeve.

The plug 49 is provided with a dial portion 52 by which the plug may be rotated manually, and the plug is retained in its opening by a ball 54 being urged into sockets 55 formed at 180° to one another. The ball 54 is pressed by a spring 56 compressed by a threaded plug 57. Preferably, the dial is provided with indicia which cooperate with a mark 60 on the handle to indicate the operative position of the dial. For example, an "O" may be provided near the edge of the dial which when registering with mark 60 indicates that the faces 10 and 32 are separated for cleaning. An arrow may be provided on the opposite side of the dial to indicate the normal operating position.

By my invention, I have provided a power driven hair extractor that will not smear or soil the skin of the operator and which may be quickly cleaned with a minimum of effort.

Although I have described but one form of the invention, it is to be understood that other forms might be adopted, all falling within the scope of the claims which follow.

I claim:

1. A hair extractor comprising a handle, hair gripping elements carried by the handle and extending from one end thereof, one of said elements consisting of a rod having a laterally pro-

jecting face at the end thereof and the other of said elements consisting of a sleeve surrounding said one element, said elements being rotatable about a common longitudinal axis; means for reciprocating one of said elements along said axis relative to the other element during rotation of said elements whereby hair is gripped and released from between the end of said sleeve and said face; and manually operable means for moving said sleeve longitudinally relative to the other member during rotation of said elements for maintaining the end of the sleeve and said face separated and inoperative to grip hair, said manual movement of said sleeve being greater in degree than the movement during reciprocation by the first mentioned means.

2. A hair extractor comprising a handle, hair gripping elements carried on the handle and extending from one end thereof, one of said elements consisting of a rod-like member having a laterally projecting face at the end thereof and the other of said elements consisting of a sleeve surrounding said member, said elements being rotatable about a common longitudinal axis, said rod-like member having a peripheral groove therein spaced from said face and normally covered by said sleeve element; means for reciprocating one of said elements along said axis relative to the other element during rotation of said elements whereby hair is gripped and released from between the end of said sleeve and said face; and manually operable means for moving one of said elements longitudinally relative to the other for maintaining the end of the sleeve and said face separated and inoperative to grip hair, the last mentioned means being operable to move the last mentioned element relative to the other a distance to uncover the groove.

3. A hair extractor comprising a handle; a rod rotatably journaled in the handle and having one end extending from the handle, said end of the rod having a laterally projecting hair gripping face; a sleeve mounted on the rod for rotation therewith, said sleeve extending to said laterally projecting face and having an end thereof cooperating with said face for gripping hair; means, comprising a cam and cam follower, for reciprocating the sleeve during rotation of said rod and sleeve for causing said sleeve to grip and release hair against said face; and manually operable means for withdrawing and retaining said sleeve withdrawn from said face independently of said means and during rotation of said rod and sleeve, the manual withdrawal of said sleeve from said face being of a greater extent than the movement of said sleeve from said face by the first mentioned means.

4. A hair extractor comprising a handle; a rod rotatably journaled in the handle and having one end extending from the handle, said end of the rod having a laterally projecting hair gripping face, said rod having a peripheral groove thereabout adjacent to said face; a sleeve mounted on the rod for rotation therewith, said sleeve extending to said laterally projecting face and having an end thereof cooperating with said face for gripping hair; means including a cam and cam follower for reciprocating the sleeve during rotation of said rod and sleeve for causing said sleeve to grip and release hair against said face; and manually operable means for withdrawing and retaining said sleeve withdrawn from said face independently of said means, the last mentioned means being operable to withdraw said sleeve from over the groove in the rod.

5. A hair extractor comprising, a handle; a rod journalled in the handle and having one end projecting from the handle, said rod having a laterally projecting face on the projecting end forming a hair gripping face, a sleeve surrounding said rod, and said sleeve and rod being rotatable about their longitudinal axis and one end of the sleeve being extendable to said face on the rod; a cam mounted on the sleeve and rotatable with the sleeve, said sleeve being slideable longitudinally relative to the cam, a cam follower carried by the handle and cooperating with the cam to reciprocate the cam longitudinally relative to the rod and sleeve as the rod and sleeve rotate; a stop on the sleeve between the cam and the projecting end of the sleeve; a spring between the cam and stop for resiliently urging the sleeve end against said face; a second stop on said sleeve adjacent said cam and engageable by the cam to positively move the sleeve contra to said spring; and a manually operable member carried by the handle and having a part engageable with said second stop for manually moving the second stop contra to said spring for withdrawing the end of the sleeve from said face on the rod.

6. A hair extractor comprising, a handle; a rod journalled in the handle and having one end projecting from the handle, said rod having a laterally projecting face on the projecting end forming a hair gripping face, a sleeve surrounding said member, said sleeve and rod being ro-

tatable about their longitudinal axis and one end of the sleeve being extendable to said face on the rod; a cam mounted on the sleeve and rotatable with the sleeve, said sleeve being slideable longitudinally relative to the cam; a cam follower carried by the handle and cooperating with the cam to reciprocate the cam longitudinally relative to the rod and sleeve as the rod and sleeve rotate; a stop on the sleeve between the cam and the projecting end of the sleeve; a spring between the cam and stop for resiliently urging the sleeve end against said face; a second stop on said sleeve adjacent said cam and engageable by the cam to positively move the sleeve contra to said spring; and a rotatable member journalled in said handle on an axis normal to the axis of the sleeve, said rotatable member having a projection eccentric to the axis of the member and engageable with the second stop for moving the sleeve against said spring.
